UNITED STATES PATENT OFFICE.

JOHN J. MORRIS, OF OCEAN BEACH, NEW JERSEY.

WATER-FILTER.

SPECIFICATION forming part of Letters Patent No. 364,599, dated June 7, 1887.

Application filed March 2, 1887. Serial No. 229,421. (No model.)

To all whom it may concern:

Be it known that I, JOHN J. MORRIS, a citizen of the United States, residing at Ocean Beach, in the county of Monmouth and State 5 of New Jersey, have invented a new and useful Improvement in Water-Filters, of which the following is a specification.

My invention relates to an improvement in water-filters; and it consists in the peculiar 10 construction and combination of devices, that will be more fully set forth hereinafter, and particularly pointed out in the claims.

In the drawings, Figure 1 is a vertical sectional view of a filter embodying my improvements, showing the same arranged in a well 15 and connected to the lower end of a pump-tube. Fig. 2 is a perspective view of my improved filter with the cap removed. Fig. 3 is a detached perspective view of the central 20 section of the filter. Fig. 4 is a perspective view of the filter complete. Fig. 5 is a horizontal sectional view of the same, taken on the line xx of Fig. 1. Fig. 6 is a detailed perspective view of the lower end of the inclosing-case.

A represents an inclosing basket- or case, which comprises the bottom cap, B, the top 25 cap, C, and the clamping-bolts D to connect the said caps together.

The bottom cap comprises the circular plate 30 b, having the vertical upwardly-projecting flange b' at its perimeter and the vertical upwardly-projecting sleeve or socket b² at its center and arranged concentrically with the 35 flange b'. From the lower side of the bottom cap project four radial ears, b³, which are arranged at equal distances apart, and are provided with openings b⁴.

The top cap, C, comprises a circular plate, 40 c, having a depending flange, c', at its perimeter, a depending sleeve, c², at its center of the same diameter as the sleeve b², and a socket, c³, on its upper side communicating with a central opening in the plate c, and adapted to 45 receive the pump-tube, as shown at Fig. 1. From the upper side of the top cap, C, project four radial ears, c⁴, which are provided with openings adapted to receive the upper ends of the clamping-bolts D.

E represents the outer annular section of the filter, comprising the outer case, e, made of wire-gauze, the inner case, e', made of the

same material and of less diameter than the outer case, e, the lower annular head, e², which closes the space between the lower ends of the 55 said outer and inner cases and secures the same together, and the upper annular head, e³, which closes the space between the upper ends of the said outer and inner cases. The space between the said cases is designed to be filled with 60 coarse gravel, as represented at e⁴ in Figs. 1 and 5.

e⁵ represents vertical strips, which extend along the outer sides of the outer case, e, and have their upper ends curved outward and 65 upward in order to form ears e⁶, by means of which the section E may be lifted from the lower cap, B.

F represents an annular section, the exterior diameter of which is somewhat less than the 70 interior diameter of the section E, and is adapted to be placed on the inner side of the said section E. The section F is similar in construction to the section E, and has the inner and outer cases, f² and f, the lower head, 75 f², and the upper head, f³, which caps close the spaces between the ends of the cases f².

f⁴ represents vertical strips, which are secured on the outer side of the section F, and the upper ends of the said strips project above 80 the top of the said section to form ears f⁶, by means of which the section F may be removed from the outer section, E.

G represents the central inner section, the exterior diameter of which is somewhat less 85 than the interior diameter of the section F. The section G is composed of the outer and inner annular cases, g and g', the bottom annular head, g², and the upper annular head, g³, which heads close the spaces between the ends of the 90 cases g and g'. The said section G is adapted to retain fine gravel, as represented at g⁴ in Figs. 1 and 5. The outer side of the section G is provided with vertical strips g⁵, the upper ends of which project above the said sections and form ears g⁶, by means of which the section G may be removed from the section F. The latter is designed to have the space between its inner and outer cases filled with 95 pieces of charcoal, as represented at f⁶ in Figs. 100 1 and 5.

It will be observed, by reference to Fig. 1, that the sleeves of the upper and lower caps, B and C, enter the central portion of the in-

terior section, G, and thus retain the same firmly in the center of the inclosing basket or case.

After the sections E, F, and G have been nested and filled with filtering material, the 5 upper cap, C, is filled with sponge, as represented at c⁵ in Fig. 1, and when the said upper cap is placed over the nested sections the sponge is compressed on the upper ends thereof. The clamping-bolts D are then inserted in the 10 openings of the projecting ears of the upper and lower caps, and when the clamping-nuts g are screwed to the upper ends of the said clamping-bolts the detachable parts of the filter are securely fastened together, as shown 15 at Figs. 1 and 4.

By reference to Fig. 1 it will be understood that the water before reaching the lower end of the pump-tube has to pass through the nested sections of the filter and through the 20 filtering material confined therein, and is thus thoroughly strained and purified.

I do not desire to limit myself to the use of my filter in connection with wells or cisterns, as it may be also advantageously employed in 25 water-coolers, tanks, and other receptacles for water.

Having thus described my invention, I claim—

1. In a filter, the combination of the central 30 annular section or case, G, having the open ends, the annular removable concentric sections surrounding the section G, and the detachable caps fitting on and closing the ends of all the sections, said caps having the central sleeves 35 fitting in the open ends of the central section, substantially as described.

2. In a filter, the combination of the central

annular section or case, G, having the open ends, the annular removable concentric sections surrounding the section G, and the detachable caps fitting on and closing the ends of all the sections, substantially as described. 4c

3. In a filter, the combination of the annular sections or cases nested within one another, and each having the concentric screens and the annular heads fixed to the ends of the screens, a sponge arranged over the upper ends of the sections or cases, and the caps B C, fitting on the ends of all the sections and connected together by bolts for confining the packing and 50 sections in place, for the purpose set forth, substantially as described. 45

4. In a filter, an annular section comprising the inner and outer perforated cases arranged concentrically one within the other to leave an intermediate chamber, the annular imperforate heads fixed to the ends of the cases, closing the spaces between the said cases, and the vertical strips secured to the annular heads, 55 substantially as described, for the purpose set forth. 60

5. In a filter, the combination of the central cylindrical section or case having the open ends, the cylindrical sections nested together and surrounding the central section, and the caps B C, extending over the ends of all the sections, substantially as described. 65

In testimony that I claim the foregoing as my own I have hereto affixed my signature in presence of two witnesses.

JOHN J. MORRIS.
